BADGE

Paul E. Jackson, Toledo, Ohio, assignor of one-half to
Anna Monnett, Toledo, Ohio

Filed Mar. 16, 1964, Ser. No. 79,001

Term of patent 14 years

(Cl. D29—6)

FIG. 1 is a plan or face view of a badge embodying my new design; and

FIG. 2 is a side or edge view of the badge shown in FIG. 1.

The essential features of the badge reside in the full line portions on the drawing. The back of the badge is essentially flat and has a shape corresponding to the front of the badge which is shown in FIG. 1.

I claim:

The ornamental design for a badge, as shown and described.
